MEANS FOR FORMING TOOTH-CROWNS.

1,121,016.

Specification of Letters Patent. Patented Dec. 15, 1914.

Application filed March 24, 1913. Serial No. 756,462.

To all whom it may concern:

Be it known that I, FERNANDO OSCAR JAQUES, Jr., a citizen of the United States, residing at Cranston, in the county of Providence and State of Rhode Island, have invented a new and useful Improvement in Means for Forming Tooth-Crowns, of which the following is a specification.

My invention has reference to an improvement in the art of dentistry and more particularly to an improvement in means for forming seamless tooth crowns of gold or other metals.

In the use of the dental system which includes steel tooth forms as shown in the United States Patent No. 971,274, issued to me Sept. 27, 1910, the gold shell is placed on the steel tooth form and compressed on to the form by driving the form and shell lengthwise into a block of wood. It has been found that considerable skill and practice is required to form a perfect tooth crown by this method, particularly so in forming gold crowns for incisor teeth having a sharp cutting edge or end and for canine teeth having a pointed end. In forming gold tooth crowns for these teeth, the cutting edge of the incisor and the pointed end of the canine steel tooth forms are liable to and are at 20 times driven through the gold shell, thereby destroying the shell, and this may occur in the hands of a skilled operator; also with this means it is impossible to obtain the natural sharp cutting edge of an incisor tooth or the natural pointed end of a canine tooth. If the thickness of the cutting edge of an incisor steel tooth former is one thirty-second of an inch, this thickness is increased proportionally by the thickness of the metal forming the gold shell.

The object of my invention is to improve the construction and method of forming seamless tooth crowns of gold or other metals, whereby the above objectionable features are eliminated and more perfect tooth crowns obtained.

Another object of my invention is to provide means for forming tooth crowns so constructed that the said means will operate simultaneously on the entire outside and inside of a shell, to form the required perfect tooth crown.

Further objects of my invention are to eliminate so far as possible skilled labor,

time and expense heretofore required in forming tooth crowns.

My invention consists in the peculiar and novel construction of means for forming metallic tooth crowns, said means having details of construction, as will be more fully set forth hereinafter and claimed.

Figure 1 is a top face view of the lower tooth crown forming member. Fig. 2 is an underside face view of the upper tooth crown forming member. Fig. 3 is a face view of a thin washer adapted to be interposed between the tooth crown forming members to vary the size of the crown. Fig. 4 is a transverse vertical sectional view taken centrally through the tooth crown forming members with the same in the open position. Fig. 5 is a longitudinal vertical sectional view through the tooth crown forming members and showing a gold shell loaded with a fusible alloy in position to be operated upon by the crown forming members. Fig. 6 is a sectional view similar to Fig. 5, showing the tooth crown forming members in the closed position and the operation of forming the tooth crown completed. Figs. 7 and 8 are front and side views respectively of the loaded tooth crown removed from the crown forming members and showing the form the fusible allow has assumed. Figs. 9 and 10 are front and side views respectively of the tooth crown after the fusible alloy has been melted out of the crown, and Fig. 11 is a vertical sectional view of a modified form for forming tooth crowns for bicuspid and molar teeth.

In the drawing 12 indicates a lower tooth crown forming member, 13 an upper tooth crown forming member, 14 a washer, 15 a gold shell, 16 a fusible metal alloy, and 17 a completed gold tooth crown. The lower tooth crown forming member 12 is preferably in the form of a hardened steel block having a smooth flat upper surface 18, in which is a central cavity 19 the bottom and sides of which has the form of approximately one half of the tooth to be crowned, a duct 20 of a predetermined size leading outward from the cavity 19, a shell gage 21 consisting of a circular hole having the size of the required shell and opening downward from the surface 18 into a recess 22 in the side of the member, a vertical shell loading cavity 23 having the size and form of

the required shell and approximately one third deeper than the length of the shell and a hole 24 extending downward from the bottom of the shell loading cavity through the member, to facilitate the removal of the loaded shell. The upper tooth crown forming member 13 is preferably of hardened steel and has a smooth flat under surface 25 on which is a raised tooth shaped portion 26 10 the sides and face of which has the form of the other half of the tooth to be crowned and fits tightly into the cavity 19 in the lower member 12, as shown in Fig. 6. The washer 14 has a central opening 27 for the raised tooth shaped portion 26 on the upper member 13. These washers are very thin and one or more of them may be interposed between the tooth crown forming members 12 and 13 to vary the size of the crown, when 20 required.

In the operation of my improved means for forming seamless tooth crowns, a gold shell 15 is gaged for size by passing the shell through the gage 21 into the recess 22. 25 The shell 15 is then removed from the recess 22 and placed in the shell loading cavity 23. The shell and upper end of the cavity is now filled with a fusible metal alloy 16 flush with the surface 18 of the member 12, 30 thereby adding to the shell an excess of fusible alloy. A small rod is now inserted into the hole 24 and the loaded shell pushed out of the shell loading cavity 23. The shell 15 now loaded with the fusible alloy 16 which extends outward from the shell approximately one third the length of the shell. The loaded shell is now placed in the tooth shaped cavity 19 in the lower tooth 35 crown forming member 18, with the protruding end of the alloy 16 adjacent the duct 20, as shown in Fig. 5. The tooth crown forming members 12 and 13 are now forced together, forming a tooth shaped cavity 28 between the members and by an equal pressure of the fusible alloy on the entire inside of the shell and an equal pressure of the forming members on the entire outside of the shell, the shell is formed into the required tooth crown. The size of the 40 duct 24 is such that a force slightly in excess of that required to form the shell into a tooth crown is necessary to force the fusible alloy into the duct. The loaded gold tooth crown, as shown in Figs. 7 and 8 is now removed from the tooth crown forming members by inserting a small rod into the duct 20, and the fusible alloy 16 melted out of the crown, thereby forming a gold tooth crown having the exact size and form of the 45 tooth to be crowned. If an incisor tooth is to be crowned the gold tooth crown will have the required sharp cutting edge of the natural tooth and if a canine tooth is to be crowned the gold tooth crown will have the required pointed end of the natural tooth.

By reversing the position of the tooth shaped cavity 28 as shown in Fig. 11 the exact form of the cusps of a natural bicuspid or molar tooth may be obtained. The tooth crown forming means are supplied in sets, one complete tooth crown forming means for each kind and size of tooth to be crowned. 70

Having thus described my invention I claim as new:—

1. Means for forming tooth crowns, comprising two members, means formed integral with each member and so constructed that when the members are together in their operative position a tooth shaped cavity is 80 formed between the members, a duct leading outward from the tooth shaped cavity through one of the members, and a ductile metal member in the tooth shaped cavity for the purpose as described. 85

2. Means for forming tooth crowns, comprising two members so constructed that when together in their operative positions a tooth shaped cavity is formed between the members, said tooth shaped cavity having a 90 length approximately one third longer than the completed crown, and a duct leading outward from the tooth shaped cavity through one of the members and a ductile metal member in the tooth shaped cavity. 95

3. Means for forming tooth crowns, comprising a member having a cavity the form of which is approximately one half of the tooth to be crowned, a member having a raised portion which fits into the cavity and has the form of the other half of the tooth to be crowned, whereby when the members are together in their operative positions, a whole tooth shaped cavity is formed between the members, a duct leading outward 100 from the tooth shaped cavity through one of the members and a ductile metal member in the tooth shaped cavity. 105

4. Means for forming tooth crowns, comprising a block shaped member preferably 110 of hardened steel and having a central cavity in its upper face, the bottom and sides of said cavity having the form of approximately one half of the tooth to be crowned, an upper member preferably of hardened 115 steel and having a raised portion on its under face, said raised portion fitting into the tooth shaped cavity and having the form of the other half of the tooth to be crowned, whereby when the lower and upper members are 120 together in their operative position, a whole tooth shaped cavity is formed between the members, a duct leading outward from the tooth shaped cavity through the lower member, and a ductile metal member in the tooth shaped cavity, a recess in the side of the lower member. 125

5. Means for forming tooth crowns, comprising a member having a cavity the form of which is approximately one half of the 130

tooth to be crowned, a member having a raised portion which fits into the cavity and has approximately the form of the other half of the tooth to be crowned, whereby when the members are together in their operative positions, a whole tooth shaped cavity is formed between the members, a duct leading outward from the tooth shaped cavity through one of the members, and a soft compressible metal member in the shell, whereby when the members are forced together into their operative positions a tooth crown is formed between the walls of the tooth shaped cavity and the soft compressible metal and the excess of soft compressible metal is forced into the duct.

6. Means for forming tooth crowns, comprising two members so constructed that when together in their operative positions a tooth shaped cavity is formed between the

members, said tooth shaped cavity having a length approximately one third longer than the completed tooth crown, a duct leading outward from the tooth shaped cavity through one of the members, a soft compressible and fusible metal member in the cavity, whereby when the members are forced together into their operative positions a tooth crown is formed between the walls of the tooth shaped cavity and the soft compressible and fusible metal member and the excess of soft compressible and fusible metal is forced into the duct.

In testimony whereof, I have signed my name to this specification in the presence of two subscribing witnesses.
